UNITED STATES PATENT OFFICE.

AUGUSTUS C. DURDIN, JR., OF CHICAGO, ILLINOIS, ASSIGNOR TO CHICAGO PUMP COMPANY, OF CHICAGO, ILLINOIS, A CORPORATION OF ILLINOIS.

SELF-CONTROLLED PUMPING SYSTEM.

1,056,752.

Specification of Letters Patent. Patented Mar. 18, 1913.

Application filed February 29, 1912. Serial No. 680,646.

To all whom it may concern:

Be it known that I, AUGUSTUS C. DURDIN, Jr., a citizen of the United States, residing at Chicago, in the county of Cook and State of Illinois, have invented new and useful Improvements in Self-Controlled Pumping Systems, of which the following is a specification.

This invention relates to self controlled pumping systems of that class which employ a pressure controlled pump for pumping water to a tank located at a higher level than the pump, as for instance a roof tank, and the main objects of the invention are to obtain greater efficiency, economy of operation and longer periods of work and rest for the pumping mechanism, and to provide such pumping system at a comparatively low cost.

In my improved pumping system I contemplate the use of different pressures in the supply pipe for operating a pressure switch to close and open an electric circuit to an electric pump. Pressure switches, operated by variations of pressure in the system, have been employed for the purpose of starting and stopping the pumping mechanism, but the difficulty encountered is that a very sensitive pressure switch is required on account of the slight variations in static pressure unless an abnormally high roof tank is used, making it practically impossible to successfully maintain the system in continuous operation. In the operation of my present system, the pressure may be caused to vary any number of pounds either way without affecting the switch, so that the delicacy of operation required in the ordinary or well known systems is wholly eliminated. Other systems contemplate the use of cables or chains running from a float in the tank to a switch located near the pump, or the use of electric conductors running from a float controlled switch mechanism at the tank to an electrically operated pump, and this invention designs to avoid the use of such connections and makes use of wide variations of pressure in the supply pipe of the system to effect the starting and stopping of the pump.

To such ends this invention consists of a pumping system for water distribution, having a pump controlled by a pressure switch, having a comparatively wide range of inactivity between its high and low act-

ing points and operated by variations of pressure in the supply pipe.

The invention further consists in the several novel features hereinafter set forth and more particularly defined in the claims.

In the drawings furnished herewith, Figure 1 is an elevation of a pumping system embodying one form of my present invention, showing the roof tank in vertical section, Fig. 2 is a detail vertical section of a valve employed in the system and Fig. 3 is a detail vertical section of a pressure switch employed in the system.

In the drawings is shown a pumping mechanism 10, preferably comprising a pump 11, of the centrifugal type, operated by an electric motor 12. Pumping mechanism of this kind is well known and requires no detailed description so far as this specification is concerned. The inlet pipe 13, 70 communicates with the pump 11, at its intake 14, and the main supply pipe 15, of the system leads from the discharge end 16, of the pump. Interposed in the supply pipe 15, and near the pump is a check valve 17, opening away from the pump, and beyond said check valve is a pipe 18, leading from the main supply pipe 15, to a pressure switch 19, that controls the motor 12. Said pressure switch may comprise any of the well known forms of pressure switch, operating under the influence of variations in pressure, and the pressure switch shown, has a diaphragm 20, within the chamber 21, which communicates with the main supply pipe 15, 80 through the pipe 18, whereby the diaphragm is continuously subjected to the pressure in the main supply pipe 15. A spring 22, held under compression between the diaphragm and a ring 23, acts to move the diaphragm 95 against the pressure on the opposite side thereof. The force of the spring is regulated by screws 24, bearing against the tapered side of the ring 23, whereby the switch may be set to operate in one direction at any desired degree of pressure. A reciprocable stem 25, operated by the diaphragm, engages with an oscillatory member 25^a, of an electric switch 26, the arrangement being such that downward movement of the stem acts 100 to break the current through the switch and upward movement thereof acts to close the circuit. This particular form of pressure switch is of course not material to my invention broadly considered, as any suitable 110

form of pressure switch operable under differential pressures and acting to control the operation of the pump, may be used. Another simple form of pressure switch that may be used in connection with this system is the one shown and described in my prior Patent No. 916957, issued March 30, 1909.

The supply pipe 15, runs to an open tank 28, preferably located on the roof of the building in which the system is installed and said pipe 15, discharges into said tank. A float controlled valve 27, preferably of the ordinary ball cock form, is provided at the upper end of the supply pipe 15, and is operated by the rise and fall of the water in the tank to close and open the water passage in the valve. Fig. 2 shows a simple form of valve in which 30, is a vertically reciprocable valve piece guided to move in the casing of the valve and arranged to seat upon a valve seat 31, surrounding the discharge port of the valve. The valve piece is moved by a lever 31¹, fulcrumed between its ends upon the casing of the valve and having one arm engaging with the valve piece and the other arm supporting a hollow ball or other float 32. This particular form of valve, however, is not material, but is sufficient for the purpose of illustration.

In the arrangement shown in the drawing, the supply pipe 15, extends to a point near the top of the tank and discharges at that point, and when a single pipe system is employed, such as is shown in the drawings, I provide an inlet to the supply pipe at a point near the bottom of the tank, the inlet in this case being in the form of a branch pipe 33, opening into the supply pipe 15, and having a check valve 34, thereon opening toward the supply pipe. It is obvious that water is free to discharge from the tank by way of the branch pipe and supply pipe. Branch service pipes 35, lead from the main supply pipe at the several floors between the pump and tank and deliver water from the tank to the desired places.

In the operation of the system, the pressure switch is set to close the circuit to the motor whenever the pressure in the supply pipe falls below a predetermined point and to break the circuit whenever the pressure in said supply pipe reaches a predetermined high point. The low pressure is determined by the height of the column of water in the supply pipe, and is the hydrostatic pressure of the column of water when the top of said column reaches a point somewhere near the bottom of the tank. For instance in a hundred foot rise, the static pressure of the column of water reaching a point near the bottom of the tank is about forty pounds per square inch, while the static pressure of a column of water reaching to the highest water level in a five to seven foot high tank is about forty-three

pounds. This small difference in pressures between the high and low points is not sufficient, however, to operate any commercial pressure switch, with precision, as it has been found that they cannot be adjusted close enough to operate successfully at variations much below ten pounds. By setting the pressure switch so as to close the circuit when the pressure falls to forty pounds and to break the circuit when the pressure reaches fifty, (a variation of ten pounds) it acts satisfactorily in connection with this system containing a one hundred foot rise of the supply pipe. If the current be turned on, the pump starts and forces water up through the supply pipe and branches, discharges water into the tank from the valve at the top of the supply pipe. As the pump continues to operate, the water in the tank rises until it reaches the float of the valve, whereupon it lifts the float and gradually closes the discharge port in the valve. The static pressure of the column of water in the supply pipe reaching the high water level is only forty-three pounds, and that is not sufficient to affect the pressure switch, but by reason of the partial closing of the discharge passage in the valve, friction is created, causing the pressure in the supply pipe to rise above the static pressure, and when the pressure reaches fifty pounds or thereabout, the pressure switch is actuated thereby and operates to break the circuit, thus stopping the motor.

Upon the stoppage of the motor and pump, the excess pressure in the supply pipe falls by reason of the leakage through the restricted discharge opening in the valve, but inasmuch as the pressure simply falls to the static pressure of the column at its high water level, it does not fall sufficiently to affect the pressure switch, consequently the motor and pump remain at rest. Water is free to discharge from the tank by way of the inlet branch 33, and through the supply pipe and its branches, and as water is drawn off, the level of the water in the tank and supply pipe falls until the predetermined low level is reached, whereupon the static pressure of the column of water has fallen to its low limit, for instance forty pounds, at which point the pressure switch acts to close the circuit and start the motor, thus permitting the pump to refill the tank.

It is obvious that the operation of this system depends upon a comparatively wide range of differential pressure in the supply pipe and that it is possible to use a comparatively low tank in which the static pressure of the water column does not vary greatly, the increased pressure being created by the partial closing of the discharge opening of the supply pipe. It is also to be observed that the pump is kept in operation and at rest during long periods of time, that

is, to say, the pump operates from the time that the water falls to its low level until the tank is filled, whereupon it stops and remains at rest until the level of the water falls to the low level, consequently the wear and tear upon the pumping mechanism, the pressure switch and other parts is reduced to a minimum.

The invention has been shown and described in connection with a single pipe system, but it is obvious to anyone skilled in the art that it is possible, just as well, to use a two pipe system containing the invention. Furthermore, the location of the valve is not limited to a point near the top of the tank, but it may be placed at the lower portion thereof, as the waterhead above the valve in this case determines the increased static pressure in the supply pipe and the increase over the static pressure is affected by the partial closing of the ball valve.

I realize that various alterations and modifications of this device are possible without departing from the spirit of my invention, and I do not therefore desire to limit myself to the exact form of construction shown and described.

I claim as new and desire to secure by Letters Patent:

1. A self controlled pumping system of the class described, comprising in combination a pump, a water supply pipe leading therefrom, a raised tank into which the supply pipe discharges, a pressure switch having a comparatively wide range of inactivity between its high and low acting points and communicating with said supply pipe and acting to start said pump when water in the tank falls to a predetermined low level and the static pressure in said supply pipe reaches a corresponding low point, and to stop the pump when water in the tank reaches a predetermined high level and the pressure in the supply pipe is correspondingly increased above static pressure therein, and means on said supply pipe whereby the pressure in the supply pipe may be increased above static pressure therein.

2. A self controlled pumping system of the class described, comprising in combination a pump, a water supply pipe leading therefrom, a raised tank into which the supply pipe discharges, a pressure switch having a comparatively wide range of inactivity between its high and low acting points and communicating with said supply pipe and acting to start said pump when the water in the tank falls to a predetermined low level and the static pressure in said supply pipe reaches a corresponding low point, and to stop the pump when the water in the tank reaches a predetermined high level and the pressure in the supply pipe is correspondingly increased above static pressure therein.

in, and a valve on said supply pipe operated by the rise and fall of water in the tank for causing an increased pressure in said supply pipe above the static pressure therein.

3. A self controlled pumping system of the class described, comprising in combination a pump, a water supply pipe leading therefrom, a raised tank into which said supply pipe discharges water, a float controlled valve in the tank and on said supply pipe for closing the passage therethrough, whereby pressure in said pipe may be increased above static pressure therein upon continued operation of the pump, and a pump controlling pressure switch, having a comparatively wide range of inactivity between its high and low acting points and communicating with said supply pipe, said pressure switch being operated by comparatively wide variations of pressure in said supply pipe, said pressure switch acting to start the pump when static pressure in the supply pipe falls to a predetermined point and to stop the pump when the pressure in the supply pipe is increased beyond static pressure therein whenever the water in the tank reaches a high level in the tank.

4. A self controlled pumping system of the class described, comprising in combination a pump, a water supply pipe leading therefrom, a raised tank into which said supply pipe discharges water and from which water discharges at a point near its bottom, a float controlled valve in said tank and on said supply pipe for partially closing the passage through said pipe whereby pressure therein may be increased above static pressure therein upon continued operation of the pump, a pump controlling pressure switch having a comparatively wide range of inactivity between its high and low acting points and communicating with said supply pipe and acting to start said pump when the water in the tank falls to a predetermined low level and static pressure in the supply pipe falls to a corresponding low point, and to stop the pump when the water in the tank reaches a predetermined high level and the pressure in the supply pipe is correspondingly increased above static pressure therein.

5. A self controlled pumping system of the class described, comprising in combination a pump, a water supply pipe leading therefrom and having a float controlled valve on its discharge end, a raised tank into which said supply pipe discharges, a branch pipe opening into said supply pipe and having a check valve thereon opening toward the supply pipe, said branch pipe serving to discharge water from the tank, and a pressure switch communicating with said supply pipe and operatively connected with the pump, said pressure switch acting to start the pump when the static pressure in the

- supply pipe falls to a predetermined low point and to stop the pump when the pressure in said supply pipe increases above the static pressure therein.
- 5 6. A self controlled pumping system of the class described, comprising in combination electric water pumping mechanism, a water supply pipe leading therefrom and having a float controlled valve at its discharge end, a roof tank into which said supply pipe discharges water, said tank having a discharge orifice, a pressure switch having a comparatively wide range of inactivity between its high and low acting points and 10 communicating with said supply pipe and in electrical communication with said pumping mechanism, said pressure switch acting to start the pumping mechanism whenever the water in the tank falls to a predetermined low level and the static pressure in the supply pipe falls to a corresponding low point and to stop the pumping mechanism when the water in the tank reaches a predetermined high level and the pressure in said supply pipe is correspondingly increased above the static pressure therein.
- 15 In witness whereof, I have hereunto signed my name, at Chicago, Cook county, Illinois, this 23d day of February 1912.
